UNITED STATES PATENT OFFICE.

KARL C. RANDALL, OF EDGEWOOD PARK, AND HERMAN K. ANSINGH, OF MURRYSVILLE, PENNSYLVANIA, ASSIGNEES TO WESTINGHOUSE ELECTRIC AND MANUFACTURING COMPANY, A CORPORATION OF PENNSYLVANIA.

CIRCUIT-INTERRUPTING DEVICE.

Application filed March 30, 1921. Serial No. 456,881.

Our invention relates to circuit-interrupting devices and particularly to an arrangement of contact members and operating mechanism therefor.

- 5 One object of our invention is to provide a device of the above-indicated character that shall be simple and durable in construction, economical to manufacture and effective in operation.
- 10 Another object of our invention is to provide an electrical protective and circuit-interrupting device that shall comprise a substantially minimum number of parts so formed and related as to facilitate the installation operations to a substantially maximum degree and that shall require only ordinary tools and ordinary skill at the place of installation.

In electrical farm equipment, it is usual 20 to receive power from a relatively high-voltage line. Switches and all other apparatus connected in circuit with high-voltage lines must, of course, be not only constructed to withstand electrical stresses but also to withstand the effects of use, time and weather.

It is, also, our aim to have all the parts 30 readily replaceable and, in particular, to have the protective parts, such as fuses and resistors, of very easy access and manipulation. With respect to the latter parts, it is desirable that they be adapted for replacement with the greatest ease and safety because of their usual position of difficult access on a pole or tower and because of the fact that such replacements may be frequently performed by the farmers themselves.

In practicing our invention, we provide a 40 relatively simple metal-frame supporting structure for disposition at the upper part of a pole or tower. Ordinary pin-type insulators for supporting connections to the line are provided with hooded contact portions projecting laterally therefrom. Tubular insulating members, pivoted at points intermediate their ends, carry yieldable contact members at their upper ends and enclose expulsion fuses in circuit with the 45 contact members and the apparatus to be supplied. A horn-gap lightning arrester and a limiting resistor are supported on the tubular insulator and connected to ground through the supporting structure. A rela-

tively long operating arm extends from the 55 device to a position near the base of the pole or tower and is connected, at its lower end, to an operating handle and a toggle mechanism by which the contact members may be maintained in their closed positions. 60

In the accompanying drawings:

Figure 1 is a front elevational view of a circuit-interrupting device embodying our invention;

Fig. 2 is a side elevational view of the 65 same;

Figs. 3, 4 and 5 are front elevational, plan, and side elevational views, respectively, of the form of stationary contact member employed by us. 70

A metal-frame structure 1, comprises longitudinal angle members 2, transverse angle members 3 and braces 4, suitably secured, as by a bolt 5, to a pole 6 and has insulators 7 of the ordinary pin type rigidly secured thereto. Caps 8 on the insulators 7 are provided with terminal connectors 9 by which they are connected to high-tension lines (not shown) through conductors 10 and are also provided with laterally-extending contact members 11 of substantially inverted channel-shape. 75

The contact members 11 are provided with bosses 11a of substantial wedge-shape at their outer ends, as shown more clearly in Fig. 4, 85 in order to cause an effective engagement with the movable contact members, as will be hereinafter described. It will be observed that the members 8, besides serving as supports for the terminals 9, also serve as stationary contact members and are formed in inverted channel-shape to protect the engaging surfaces of the relatively movable contact members from rain and snow. 90

A transversely-extending shaft 12, supported, near its ends, in the angle members 2, supports brackets or lever arms 13 which project outwardly therefrom. 95

The arms 13 are provided with clamping portions 14 which co-operate with clamping members 15 and bolts 16 to secure tubular insulating members 17 intermediate the ends of the latter. The insulating members 17 are provided, at their upper ends, with cap members 18 to which relatively thin yieldable contact members 20 are secured. The outer ends of the contact fingers 20 normally incline toward one another but, when brought 100 105

into engagement with the outer end of the boss 11a of the channel member 11, are caused to spread as shown in Fig. 1 and thus effectively engage the contact members 11.

The cap members 18 are provided with projections to which clamping members 24 and 28 are secured, and these clamping members serve as supports for horn-gap members 30.

Each of the clamping members 24 and 28 supports a member 32 of inverted cup-shape for the reception of one end of a limiting resistor which extends into a socket-like terminal 34 that is supported from the clamping member 15. The resistors 33 are slidably supported in the members 32 and 34 and may be readily slid upwardly to permit removal of the lower ends from the terminals 34 and, consequently, from the cup-shaped members 32.

Each of the insulators 17 is provided with a longitudinal perforation 35 for the reception of an explosion fuse or other conductor member. The explosion fuse is retained in place by a cap member 36 that is detachably secured to the bottom of the insulator. The explosion fuses connect the cap members 18 and the contact members 20 with terminals 37.

The shaft 12 is provided with a bell-crank lever 38 of insulating material. A rod 39 has one of its ends pivoted on the outer end of the bell-crank lever 38 and its other end pivotally connected, by a bolt 40, to an operating lever that is pivotally supported on the pole 6 by a bolt 42. The relation of the bolts 40 and 42 is such that, when the operating lever 41 is in its upper position and

the contact members 20 and 11 are in engagement, the force on the lever caused by the weight of the moving parts is directed to hold the lever 41 in its upper position. A projection 43 is provided to co-operate with the bottom portion 44 of the lever 41 by means of a pin or padlock (not shown) for locking the moving parts of the apparatus against movement.

A pair of springs 45, each of which has one end fastened to the shaft 12 and its other end to one of the angle members 2, serve as cushions for the moving parts.

While we have shown and described a particular form of our invention, changes may be effected therein without departing from the spirit and scope thereof, as set forth in the appended claim.

We claim as our invention:

In an electrical protective and circuit-interrupting device, the combination with an elongated stationary contact member of substantially inverted channel-shape, of a relatively movable co-operating structure therefor comprising a rotatable supporting shaft extending at substantially right angles to the said channel and a yieldable contact member formed and related to the stationary contact member to be readily guided into and out of engagement with the under side of the said channel member and to compensate for variations in the distance between the latter and the center line of the shaft.

In testimony whereof, we have hereunto subscribed our names this 25th day of March, 1921.

KARL C. RANDALL.
HERMAN K. ANSINGH.
